CHRISTMAS MOBILE OR THE LIKE

Otto Kadmon and Alice Kadmon, both of 144-37 76th
Road, Flushing, N.Y. 11367

Filed Feb. 10, 1967, Ser. No. 5,763

Term of patent 7 years

(Cl. D29—1)

FIG. 1 is a front perspective view of a Christmas mobile or the like showing our new design; and

FIG. 2 is a rear view thereof as it appears with the center element in inverted position.

We claim:

The ornamental design for a Christmas mobile or the like, substantially as shown and described.
